DESIGN FOR A CONDIMENT DISPENSER

Emma M. Swift, Birmingham, Mich.

Application August 2, 1946, Serial No. 132,252

Term of patent 7 years

(Cl. D44—22)

To all whom it may concern:

Be it known that I, Emma M. Swift, a citizen of the United States, residing at 875 Stanley Street, in the city of Birmingham, county of Oakland, and State of Michigan, have invented a new, original, and ornamental Design for a Condiment Dispenser, of which the following is a specification, reference being had to the accompanying drawings, forming part thereof.

Fig. 1 is a view in side elevation; and

Fig. 2 is an enlarged sectional fragmentary view of a condiment dispenser, showing my new design.

I claim:

The ornamental design for a condiment dispenser, as shown.

EMMA M. SWIFT.
